UNITED STATES PATENT OFFICE.

ELMER F. ALTMAN, OF MINNEAPOLIS, MINNESOTA, ASSIGNOR OF ONE-HALF TO ORIN M. OULMAN, OF MINNEAPOLIS, MINNESOTA.

AUTOMOBILE-CHASSIS.

1,124,578.

Specification of Letters Patent. Patented Jan. 12, 1915.

Application filed September 11, 1913. Serial No. 789,302.

To all whom it may concern:

Be it known that I, ELMER F. ALTMAN, a citizen of the United States, residing at Minneapolis, in the county of Hennepin and State of Minnesota, have invented certain new and useful Improvements in Automobile-Chassis; and I do declare the following to be a full, clear, and exact description of the invention, such as will enable others skilled in the art to which it appertains to make and use the same.

This invention relates to motor vehicles, and more especially to the framework thereof; and the object of the same is to produce an improved support for the driving shaft at points in front and in rear of the transmission, and for the jack shaft which is geared to the rear end of said driving shaft in certain constructions.

With this object in view the invention consists in the details of construction hereinafter more fully described and claimed and as shown in the drawings wherein—

Figure 1 is a side elevation of this mechanism complete, with a part of the housing in section. Fig. 2 is a front elevation of this mechanism, looking at Fig. 1 from the left hand. Fig. 3 is a cross section taken through the jack shaft. Fig. 4 is an elevation of one of the yokes in the slightly different form. Fig. 5 is a side elevation in detail of the parts forming one member of the housing for the jack shaft.

In the type of motor car construction here-
with illustrated, the rear end of the power
shaft P extends into the housing H of the
transmission mechanism T which is disposed
between and beneath the side bars F of the
main frame, and the main shaft M projects
from the rear end of said housing and is
geared at G and G' to a transverse shaft
herein called the "jack shaft" J carrying a
sprocket wheel S which in turn is connected
by a chain (not shown) with the rear or
driving axle. Rotary power applied to and
through the shaft P is communicated to the
main shaft M when the transmission mecha-
nism T is properly set, and from the main
shaft it is communicated through the gears
to the jack shaft J from which it is com-
municated to the rear axle. Therefore there
is considerable strain tending to separate the
teeth of the intermeshing gears G and G'
whenever the machine is started and is
driven up a hill or carries a heavy load, and

the purpose of the present invention is to provide a support for the rear end of the main shaft M and for both ends of the jack shaft J whereby these parts will be held ever in proper relative position and will yet be accessible for inspection and repair. When the jack shaft is connected by a sprocket chain with the rear axle, in whichever direction the machine is moving there is considerable tension on the working side of said chain tending to draw the jack shaft to the rear and disengage the teeth of its gear G' from the teeth of the power gear G; and therefore it is desirable that the bearings for said jack shaft be suitably braced to the framework or chassis F of the motor vehicle to resist this strain as well as the other strain above referred to. As is well known to engineers familiar with this type of machinery, the rear axle moves up and down with reference to the frame or chassis as the wheels pass over obstructions in the road or as the frame is depressed by the load upon it; and when said chain is surrounded by a housing, the latter must be movably connected with the support for the bearings of the jack shaft so that the housing sections may telescope slightly as the chain is tightened or loosened and so that the rear section may rise and fall while the forward section remains rigidly connected with the chassis. The details of this housing form no part of this application, nor is any claim made for the detailed construction of the parts thus far described and referred to by reference letters.

Coming now to the present invention, the reference numeral 1 designates a yoke of substantially inverted U-shape, having a dropped center 2, seats 3 at opposite sides of said center, eyes 4 adjacent said seats for a purpose to appear, upright side arms 5 deflected outward at their upper ends as at 6, and upright flanges 7 at the outer extremities of said outwardly deflected portions 6, which flanges are bolted within the frame F as will be clear. Mounted within this yoke is an element of the chain-housing forming part of my companion application above referred to, and the same is herein shown as consisting of a box B inclosing the power gear G, resting on the seats 3 and bolted to the upright arms 5 as at 8, a removable cover plate C for said box whereby access may be had to its interior for obvious

purposes, and two eyes I, projecting to the rear from the box and adapted to receive the jack shaft ends in a manner yet to be described, and the box carries a large ring R which incloses the jack shaft and the intermeshing gears, and which itself has packing r around its edge co-acting with the rear member of the chain housing as explained in my companion application. As above stated, I lay no claim to this detail, or to anything in this specification which is designated on the accompanying drawings by reference letters. The dropped center 2 of the yoke 1 is by preference shaped to conform with the bottom of the box B, and yet to permit the attachment and detachment of the ring R. When said ring is removed, access may be had to the eyes I. These receive bearings 10 which may be of the ball or the roller type and by preference are screwed into the eyes as shown, and the ends of the jack shaft J are mounted in said bearings. On this shaft is fixed the driven gear G' which meshes 25 with the driving gear G, and also the sprocket S which, as above stated, is connected by a chain, (not shown) with a similar sprocket on the rear axle. When now access is desired to the interior for purposes 30 of inspection, the top plate or cover C is removed. If this be not sufficient, the ring may be detached and drawn out of place, and that will permit access to the interior. The jack shaft and the parts carried thereby can be entirely removed by running the 35 bearings 10 out in the eyes and until one end of the jack shaft can be slipped out of place, after which by proper manipulation it may be properly withdrawn. These bearings, or 40 at least that bearing which may be said to be behind the gear wheel G', are or is of the nature of a shaft bearing to resist the strain thrown onto the jack shaft by the intermeshing of the gears G and G'. In addition, they also take the tension of the chain, and for this reason it may be wise to brace 45 the yoke 1. For this purpose rods 11 are passed through the eyes 4 and led forward and obliquely upward and are connected 50 with the frame F in any suitable manner.

Another feature of my invention is the particular form of support for the power shaft P, just in front of the transmission housing H. This consists of a yoke 13 having a dropped center 12, oblique side arms 15 having eyes 14 near their outer ends, and flanges 17 at the outer extremities of said arms which are bolted to the chassis frame F like the flanges 7 on the yoke first above 55 described. If this detail be employed in connection with that above mentioned, the forward ends of the rods 11 will pass through and be bolted in the eyes 14 as shown. The dropped center 12 stands beneath a removable plate H' at the front end 60

of the housing H and supports the same as shown, the yoke being here flanged as at 15, to prevent longitudinal movement of this part of the housing.

The shaft bearing is held in position by a 70 cover which is shown in Fig. 2 as consisting of an arched member 16 passing over the forward portion of the housing H and bolted at its ends as at 18 to the yoke; but the same may be broken away at its center so 75 that the arch consists of two members as shown at 19 in Fig. 4 overlying this portion of the housing and connected by the same bolts 18. In fact, considerable latitude will be allowed the builder in this respect, as the 80 transmission mechanism and its housing are often purchased in the market and assembled in the motor vehicle being built, and the framework and therefore the yokes thereof must be adapted to the shape of the 85 housing on said transmission mechanism. The latter needs no detailed description, as its structure is unimportant to the present invention and its operation is well known. With this member, however, as with the 90 other yoke member 1 above described, I prefer that the dropped center be left open or covered by a removable member 16 or 19, with the obvious purpose of permitting the mechanism carried thereby to be lifted out of 95 place when it becomes necessary to repair the same.

The materials and proportions and details of construction further than as above set forth are not essential.

What is claimed as new is:

1. In a motor vehicle, the combination with the chassis frame, of a pair of yokes each having a dropped center, diverging arms, and means for connecting the outer extremities of the latter with said frame, one yoke having eyes through its arms near their outer ends and the other having eyes through its body near its dropped center, and rods connecting the eyes in one yoke 100 with those in the other, for the purpose set forth.

2. In a motor vehicle, the combination with the chassis frame, a yoke secured across the same and having a dropped center, and a box mounted within the dropped center of said yoke and having a pair of rearwardly projecting eyes; of a driving shaft having a power gear standing within said box, bearings removably mounted in said eyes, a jack 115 shaft mounted in said bearings and having a driven gear meshing with the power gear, and connections between said jack shaft and the driving axle.

3. In a motor vehicle, the combination 125 with the chassis frame; a yoke secured across the same and having a dropped center, and a box mounted within the dropped center of said yoke and having a pair of rearwardly projecting eyes; of a driving shaft having a 130

power gear standing within said box, bearings removably mounted in said eyes, a jack shaft mounted in said bearings and having a driven gear meshing with the power gear, 5 a sprocket fast on said jack shaft and adapted to be connected with the driving axle of the vehicle, and rods connecting the lower portion of said yoke with the chassis frame at a point forward of the yoke, for the purpose set forth.

4. In a motor vehicle, the combination with a frame, a yoke across the same, a box removably mounted within said yoke and having a pair of parallel eyes projecting 15 from the rear, and a ring detachably connected with said box; of a power shaft pro-

jecting through the front of said box and carrying the driving gear, bearings removably mounted in said eyes, a jack shaft journaled in said bearings and having a driven gear meshing with the driving gear, the eyes, bearings, shaft and driven gear being inclosed within said ring, and connections between said jack shaft and the rear axle of the motor vehicle. 20 25

In testimony whereof I have hereunto set my hand in presence of two subscribing witnesses.

ELMER F. ALTMAN.
